UNITED STATES PATENT OFFICE.

CHARLES L. GOODRUM, OF NEW YORK, N. Y., ASSIGNEE, BY MESNE ASSIGNMENTS, TO
WESTERN ELECTRIC COMPANY, INCORPORATED, A CORPORATION OF NEW YORK.

TELEPHONE-EXCHANGE SYSTEM.

1,171,429.

Specification of Letters Patent.

Patented Feb. 15, 1916.

Application filed July 23, 1915. Serial No. 41,480.

To all whom it may concern:

Be it known that I, CHARLES L. GOODRUM, a citizen of the United States, residing at New York, in the county of New York 5 and State of New York, have invented certain new and useful Improvements in Telephone-Exchange Systems, of which the following is a full, clear, concise, and exact description.

10 This invention relates to telephone exchange systems employing machine switching, and particularly to systems or exchanges consisting of a number of offices. In trunking between orifices in such exchanges, it is the practice to relay or repeat the impulses for setting the automatic switches at the distant office from the incoming office to the distant office. Due to the conductive separation of the trunk circuit 15 at the repeater by condensers, it is necessary to provide means for preventing such condensers from changing the character of the impulses relayed to the distant office to set the switches thereat, which they would otherwise do in discharging. Repeaters have been employed wherein relays disconnect the condensers from the trunk while the impulses are being transmitted. After the switches at the distant office have been 20 set, these relays again connect the condensers to the trunk to complete the talking circuit.

25 This invention provides a highly efficient repeater circuit, wherein the use of such relays, or their equivalents, is rendered unnecessary, and consists in inductively uniting the incoming line with the outgoing trunk by a low capacity repeating coil, and including in circuit with the repeater windings on the incoming side a relay which is 30 adapted to be operated intermittently by the sender, in accordance with the digits of the wanted number, to open and close a shunt circuit about a stepping relay at the 35 distant office to set the switches thereat.

40 The invention will be more readily understood when described by reference to the accompanying drawing which illustrates only so much of a telephone system as is 45 necessary for a comprehension of the invention.

45 The calling subscriber at substation A upon removing his receiver would set in motion a line finder whose brushes 23, 17

and terminals 18, 22 only are shown, since such switches are well known in the art. The calling subscriber is thus connected to a first selector which is then set by the sender S operated by the calling subscriber in the well-known manner to step the 60 brushes 15, 25 of the first selector in operative relation to a group of trunks terminating in the office containing the wanted line. The first selector would then in the well-known manner automatically pick out 65 an idle one of these trunks. The operation of the apparatus up to this point is well known and therefore need not be described. It may be of the type shown in U. S. Patent 1,118,910. Upon the finding of the idle 70 trunk, the stepping relay 10 is energized over the following circuit: free pole of battery, left winding of relay 10, conductors 11, 12, left-hand upper winding of repeating coil R, conductor 13, terminal 14, brush 75 15, conductor 16, finder brush 17, finder terminal 18, conductor 19, sender S, through the telephonic apparatus at substation A; conductor 21, finder terminal 22, finder brush 23, conductor 24, brush 25, terminal 80 26, conductor 27, lower left winding of repeating coil R, conductors 28 and 29, right winding of relay 10 to ground. The relay 10 at its right armature and front contact closes the following circuit to energize a 85 slow relay 28': free pole of battery, relay 28', conductor 29', right armature and front contact of relay 10 to ground. This relay at its armature and front contact prepares a circuit for a slow relay 30. Relay 90 28' at its outer armature and front contact closes the following circuit for stepping relay 60 at the distance switch, which in the present embodiment is a connector: free pole of battery, outer armature and front 95 contact of relay 28', conductor 33, lower right winding of repeating coil R, conductors 34 and 35, windings of relay 60, conductors 36 and 37, upper right winding of repeating coil R to ground. The subscriber at 100 substation A now operates his sender S, which interrupts the line circuit in the well-known manner a number of times, corresponding to the digit of the called number involved in this particular selecting operation. Each time the stepping relay 10 releases its left armature, the stepping relay 105 60 at the distant switch is operated due to

the opening of the following shunt path: free pole of the battery, outer armature of relay 28', conductor 33, conductor 38, left armature and front contact of relay 10, 5 conductor 39, right armature and front contact of relay 30, conductor 40, conductor 37, upper right winding of repeating coil R to ground. Relay 60 at the distant connector is thus intermittently operated. This relay 10 at its armature and contact operates the primary magnet at the connector, which magnet elevates the brushes 41, 42 to the group containing the terminals of the wanted line in the well-known manner. At the end of 15 this series of interruptions, when the sender completely restores and maintains the line relay 10 energized, the relay becomes de-energized. At its right armature and front contact this relay interposes a break in the 20 shunt about relay 60 at the connector, which thereupon remains energized. By maintaining its back contact open the usual slow change-over relay, dependent for its continued energization on the back contact of 25 this relay, will become deenergized to release the side switch, to shift the circuit leading from the contact of the relay 60 from operative relation to the primary magnet of the connector, and into operative relation with the secondary magnet thereof. 30 The subscriber at substation A now operates the sender S, in accordance with the units digit of the number of the wanted line, whereupon the circuit of relay 10 is again intermittently interrupted, which in 35 turn intermittently operates the relay 60 at the connector by shunting the same. Relay 60 in turn transmits impulses to the secondary magnet of the connector to step the brushes 41, 42 to the terminals of the wanted line. The line is then tested. If idle, ringing current is sent thereover, or if busy, a busy signal is sent back to the calling subscriber. The apparatus for accomplishing 40 these functions may be similar to that shown in the patent mentioned. When the subscriber at substation B removes his receiver in response to the signal, the following circuit is closed to supply him with talking current: free pole of the battery, left winding of relay 45, conductor 46, conductor 47, brush 41, terminal 43, sender S', telephonic apparatus at substation B, conductor 48, terminal 44, brush 42, conductor 49, 50, right winding of relay 45 to ground. Talking current is supplied to the calling party over the circuit for relay 10 previously traced. The maintained energization of the stepping relay 10 at the end 55 of units selection causes the deenergization of slow relay 30, which at its left armature and back contact closes a shunt circuit about the windings of relay 10, and the retraction of its right armature opens the connection of battery with trunk conductor 37.

When the calling subscriber at substation A restores his receiver, he interrupts the circuit of relay 10. This relay allows its armature to fall back. The left hand armature in falling back, opens its front contact 70 and causes the deenergization of the slow relay 28', which completes the circuit of the release magnet R' of the first selector over the following circuit: free pole of battery, magnet R', conductor 54, brush 55, terminal 56, conductor 57, armature and back contact of relay 28', conductor 32, right armature and back contact of relay 10 to ground. The outer armature of relay 28' in falling back, opens the circuit of relay 60 75 of the connector, which, by opening its front contact for a relatively long interval of time, deenergizes a slow relay controlled at said front contact in the well-known manner, this slow relay closing the release circuit of the connector. The apparatus is now 80 restored and ready to be used in establishing another connection.

What is claimed is:

1. In a telephone exchange system, the 90 combination with a talking circuit divided into sections, a repeating coil uniting said sections inductively, of a relay included in one section of said circuit, a sender adapted to operate the same, a relay included in the 95 other section of said circuit, a shunt circuit about said last-mentioned relay controlled by said first mentioned relay, and an automatic switch adapted to be set by the impulses so produced. 100

2. In a telephone exchange system, the combination with telephone lines, offices wherein said lines terminate, a trunk circuit interconnecting said offices and divided into incoming and outgoing sections, a repeating 105 coil uniting said sections inductively, means for associating a calling line with the incoming section of said trunk, a stepping relay in said section adapted to be energized when a calling line is connected thereto, a 110 relay adapted to be operated by said stepping relay and to apply current to the outgoing section of said trunk, a stepping relay included in said trunk at the distant office adapted to be energized by the closure of 115 said circuit, a shunt about said stepping relay adapted to be closed upon each operation of said stepping relay in the incoming section, and an automatic switch adapted to be set by said stepping relay at the distant 120 office.

3. In a telephone exchange system, the combination with telephone lines, offices wherein said lines terminate, a trunk circuit interconnecting said offices and divided into 125 incoming and outgoing sections, a repeating coil uniting said sections inductively, means for associating a calling line with the incoming section of said trunk, a stepping relay in said section adapted to be energized when a 130

calling line is connected thereto, a slow relay adapted to be operated from the front contact of said stepping relay and to apply current to the outgoing section of said trunk, a 5 stepping relay included in said trunk at the distant office energized by the closure of said circuit, a shunt circuit about said relay adapted to be closed upon each operation of said stepping relay in the incoming section, 10 and an automatic switch adapted to be set by said stepping relay at the distant office.

4. In a telephone exchange system in combination with telephone lines, offices wherein said lines terminate, a trunk circuit inter- 15 connecting said offices and divided into incoming and outgoing sections, a repeating coil uniting such sections, means for associating a calling line with the outgoing section of said trunk, a stepping relay 10 in the incoming section and adapted to be energized when a calling line is connected thereto, a slow relay 28 adapted to be energized from the front contact of said stepping relay and to apply current to the out- 20 going section of said trunk, a second slow relay 30 adapted to be operated from the

back contact of said stepping relay, a stepping relay 60 included in said trunk at the distant office energized by the closure of said circuit, a shunt circuit about said relay controlled 30 at front contacts of said slow relay 30 and stepping relay 10 and adapted to be closed each time the stepping relay is energized, and an automatic switch adapted to be set by said stepping relay 60 in the distant office. 35

5. In a telephone exchange system, the combination with a talking circuit divided into sections, means for inductively uniting said sections including feed coils and a source of current, an electromagnet included 40 in one section of said circuit, a sender adapted to operate the same, an electromagnet included in the other section of said circuit, a shunt circuit about said last mentioned magnet controlled by said first mentioned magnet, and an automatic switch adapted to be set by the impulses so produced. 45

In witness whereof, I hereunto subscribe my name this 21st day of July A. D., 1915.

CHARLES L. GOODRUM.
